CONDENSATION TRAP

Leonard G. Marcotte and Alvin Q. Marcotte,
St. Paul, Minn.

Application September 28, 1956, Serial No. 612,850

2 Claims. (Cl. 60—29)

This invention relates with improvement in condensation traps, and deals more particularly with a condensation trap which is used in the exhaust line of an automobile engine, or the like.

Most mufflers or silencers produced at the present time are made of a metal which is susceptible to rust. When condensation collects in these mufflers, tend to oxidize the metal and to cause erosion. As a result, condensation tends to form holes in the muffler and accordingly, early replacement is necessary. An object of the present invention lies in the provision of a condensation trap between the automobile engine and the muffler which tends to collect the moisture and to eliminate this from the line, thereby definitely prolonging the life of the muffler.

It is a known fact that condensation collects in the exhaust lines of automobiles. This is particularly true in colder climates where the gases leaving the internal combustion engine which are heavily laden with moisture contact the cold surfaces of the exhaust pipe to precipitate the moisture on the surface of the pipe. Once the exhaust pipe and the muffler are heated by the exhaust gases, the moisture tends to evaporate and passes through the system without causing damage thereto. On the other hand, where the motor of the vehicle is not run for a sufficient time to cause evaporation of the moisture in the line, this moisture collects in the muffler and eventually causes the destruction of the same. In cold climates, this condensation is perfectly obvious in exhaust systems, and actually extends through the tail pipe of the vehicle causing moisture to drip from the end of the tail pipe which is at a considerable distance from the muffler.

One of the difficulties lies in the fact that the tail pipe of the vehicle usually is bent to extend over the rear axle of the vehicle. In present day automobiles, the muffler is on an extremely low part of the automobile making it necessary for the tail pipe to be bent upwardly to pass over the rear axle. Thus moisture in the muffler even when evaporated, must pass over this raised portion of the tail pipe to be exhausted through the rear end of the same. If the tail pipe of the vehicle is not heated sufficiently to prevent condensation from collecting thereon, any condensation might well tend to drain back into the muffler to cause deterioration thereof.

It is an object of the present invention to provide a condensation trap which is mounted upon the exhaust line forwardly of the muffler. This trap is designed to receive any condensate which is collected by the exhaust line prior to the time that the exhaust enters the muffler. As condensate normally collects during the time the exhaust pipe is cold and when the engine of the vehicle is first started, the major portion of the condensate may collect in the trap. Thus most of the injury to the tail pipe of the vehicle may be avoided by the arrangement which is provided.

A feature of the present invention lies in the fact that the condensate trap may be applied to the exhaust pipe

2

of a vehicle which has been previously produced. In order to apply the trap, it is only necessary to cut a hole in the bottom of the exhaust line leading to the muffler. The condensation trap is designed to partially encircle the exhaust line in alignment with the hole cut in this pipe. Moisture collecting in the exhaust line will therefore drain into the condensate trap before entering the muffler thereby greatly prolonging the life of the muffler itself.

10 A further feature of the present invention lies in the fact that the condensate trap is provided with a collecting portion which is designed to extend up into the exhaust pipe of the vehicle. As a result, the portion of the gases which are heavily laden with liquid will strike this projection and be deflected downwardly into the trap thereby eliminating the moisture from the exhaust gases.

15 A further feature of the present invention lies in the fact that the condensate trap is provided with a thickness of insulating and absorbent material into which the liquid condensate is collected. The thickness of material in the trap is sufficient to prevent the loss of pressure in any great amount thus not having any effect on reducing the effectiveness of the muffler in silencing the sounds of the engine. At the same time, the moisture may drain entirely through the body of material if sufficient moisture collects so that moisture can be drained from the exhaust system without harmful effects to the muffler or to the tail pipe.

20 An added feature of the present invention lies in the fact that the condensate trap is closely associated with the exhaust line of the vehicle, the major portions thereof being separated from the exhaust line only by a gasket of material capable of withstanding heat. As a result, the moisture trap in itself gradually heats as the moisture collects therein, but the rate at which the temperature rises in the moisture condensing trap is materially less than the rate at which the muffler and tail pipe increase in temperature.

25 30 35 40 45 As a result, moisture which is collected within the body of absorbent material within the trap, if the moisture is not sufficient to drain through the lower opening thereof, will gradually vaporize, and pass through the muffler and tail pipe at a time when these elements are heated to such an extent that moisture will not collect thereon. As a result, the moisture which has collected in the trap, may be expelled without harmful effects either to the muffler or to the tailpipe.

These and other objects and novel features of the present invention will be more clearly and fully set forth in the following specification and claims.

40 In the drawings forming a part of this specification: Figure 1 is a diagrammatic view showing a vehicle engine, an exhaust line, the moisture trap, the muffler, and a portion of the tailpipe, showing the relationship of parts in the system.

45 Figure 2 is a cross sectional view through the moisture trap showing the arrangement of parts therein.

50 Figure 3 is a top plan view of the moisture or condensation trap removed from the exhaust pipe.

55 Figure 4 is a diagrammatic cross-sectional view on the irregular section line 4—4 of Figure 2.

60 65 70 In general, the present device is used in connection with an internal combustion engine which is indicated in general by the numeral 10. This internal combustion engine is connected by an exhaust pipe 11 to a muffler or silencer 12 which in turn is connected to a tail pipe 13. While not illustrated in the drawings, it is common knowledge that the tail pipe 13 is usually bent upwardly to extend over the rear axle of the vehicle in modern day automobiles. Thus it is true that the muffler is the lowest part of the system between the automobile engine 10 and the

rear end of the tail pipe 13, not illustrated in the drawings.

In order to prevent moisture from collecting in the muffler trough, I provide a moisture trap which is indicated in general by the numeral 14. This moisture trap is located in the exhaust pipe 11 forwardly of the muffler 10. As a result, much of the moisture which is condensed in the exhaust pipe at the time the vehicle engine is started into motion is collected in the trap 14 rather than in the muffler 12. As a result, the life of the muffler is indefinitely increased.

In general, the condensation trap includes a trough shaped member 15, illustrated in Figures 3 and 4 of the drawings, which is designed to fit the curvature of the exhaust pipe 11 at the horizontal portion 16 thereof. As illustrated in the drawings, the trough shaped portion 15 which is usually formed of metal, is lined with an inner lining of a gasket forming material such as asbestos' sheathing or the like. Thus the trough shaped member 15 may be applied to the exhaust line 11 without the loss of gases through the walls of the exhaust pipe which would create a considerable increase in the noise produced by the engine.

As is indicated in Figure 2 of the drawings, a generally rectangular opening 17 is cut in the lower portion of the exhaust pipe 11 in the horizontal portion 16 thereof. This opening 17 is of sufficient size to permit the exhaust of liquid which has condensed within the exhaust pipe 11. Attached to the undersurface of the trough shaped member 15 is provided a generally cylindrical trap portion 19. While this portion is described as cylindrical, it should be obvious that the particular outline shape is of little importance.

The body 19 of the condensation trap is provided with a top closure 20 which covers the major portion of the upper surface of the trap. However, as indicated in Figure 2 of the drawings, one portion 21 of the top closure 20 is bent upwardly and another portion 22 of this same cover 20 is bent downwardly to provide an opening passage 23 therebetween. The upwardly projecting portion 21 projects above the surface of the trough shaped member 15 so that gases passing through the exhaust pipe, and particularly those which are heavy with moisture, will be directed downwardly into the trap body 19.

The body 19 of the condensation trap which has been described for the purposes of illustration as being cylindrical in form, includes a cone shaped bottom extremity 24 having a central opening 25 therein. A disc 26 of coarse screening or the like extends across this cone shaped bottom 24 and a finer screen 27 overlies the coarser screen 26. This arrangement is provided to support the body of insulation and of absorbent material 29 which normally rests upon the screen 27. If the absorbent material 29 is of sufficient body to rest upon the coarse screen 26 without disintegration, or if this porous body is possessed of sufficient strength to bridge the lower end of the condensate trap, the screens 26 and 27 may be eliminated.

A fine screen 39 overlies the body of insulation material 29 and a coarser screen 40 overlies the finer screen 39. As a result, the insulation and absorbent material is confined between the screen structures thereby permitting a liquid to absorb thereinto, without disintegration of the absorbent material, and so that this material cannot crumble or otherwise disintegrate and pass through the lower opening 25.

As an example of the material which may be used to form the filter 29, ground asbestos has been effectively used. However, any material which is resistant to heat and which tends to absorb moisture may be useful for this purpose. For example expanded vermiculite or expanded mica granules may be employed. Materials of this type, which are resistant to heat and which tend to cling to moisture, will hold the moisture entrapped until the body of the trap becomes sufficiently heated to vapor-

ize the liquid. It should be noted that by the time the liquid within the trap is vaporized, the body of the muffler and of the tail pipe of the exhaust system is heated to a sufficient extent so that moisture will pass there-through without condensation.

Clamps such as 41 may encircle the exhaust pipe 11 and the trough shaped portion 15 of the condensation trap to hold the two parts tightly assembled. The gasket 46 of molded sheet asbestos or other similar material, will prevent the escape of the gases about the opening 17.

Thus it will be seen that a condensate trap is provided between the vehicle engine and the vehicle muffler which tends to collect the moisture which condenses on the pipe particularly when the exhaust pipe is extremely cold and when the exhaust gases are laden with moisture, a condition which normally exists in an automobile engine when the engine is started in cold weather. The moisture which is entrained in the exhaust gases tend to collect and to be condensed on the exhaust pipe until the time this exhaust pipe is heated sufficiently to evaporate this moisture. The liquids which are condensed on the exhaust pipe, drain into the condensate trap and are absorbed by the material 29 therein. In the event an excess of moisture is experienced, the moisture will drain completely through the material in the filter 29 and will drain through the drain opening 25.

The virtually moisture free exhaust gases pass into the muffler 12 and into the tail pipe 13, heating these parts to a temperature capable of evaporating moisture. However, as the muffler 12 is a relatively large diameter and all of the muffler is not subjected to the same heat, an excess of moisture may collect in this muffler particularly when the vehicle engine does not remain in operation for a very long period. This causes the moisture to erode the inner surface of the muffler and to eventually cause failure thereof.

With the present system, the excess of moisture is collected in the moisture trap and this moisture will either drain from the bottom of the trap, or remain entrapped in the body of insulation and absorbent material until the outer body of this trap is heated sufficiently to evaporate the moisture. In such an event, the evaporated moisture will be carried by the exhaust gases completely through the muffler and through the tail pipe as these parts have by this time been heated to a temperature above the temperature of the trap.

In accordance with the patent statutes, the principals and construction of the present invention have been described, and while it has been attempted to illustrate the best embodiment thereof, obvious changes may be made within the scope of the following invention without departing from the scope thereof.

We claim:

1. A condensation trap for attachment to a straight portion of a conventional exhaust pipe extending between an internal combustion engine and a muffler and having an opening in the lower surface thereof, the trap comprising a hollow body having top, bottom and side walls, said top wall having one portion thereof bent upwardly to extend through the opening into said exhaust pipe and another portion thereof bent downwardly into said body to provide an opening through said top wall, said bottom wall having an opening therethrough to permit the escape of condensation that enters through said top opening, absorbent material supported within said body intermediate said upper and lower openings, and means to clamp said hollow body to the exhaust pipe.

2. A condensation trap for attachment to a straight portion of a conventional exhaust pipe extending between an internal combustion engine and a muffler and having an opening in the lower surface thereof, the trap comprising a hollow body having top, bottom and side walls, said top wall having one portion thereof bent upwardly to extend through said opening into the exhaust

pipe and another portion bent downwardly into said body to provide an opening through said top wall, said bottom wall having an opening therethrough to permit the escape of condensation that enters through said top opening, absorbent material supported within said body intermediate said upper and lower openings, said hollow body having trough shaped sections extending in opposite directions from the opposite sides of said top wall in general longitudinal alignment with said bent portions, and clamping means adopted to encircle said trough 10 shaped sections and said exhaust pipe to retain said trap

in fixed relation with said pipe and with said bent portions oriented so as to cause said top opening to face in a direction counter to gas flow through the exhaust pipe.
